10 The object of the present invention is to provide an ornamental and attractive inkstand; and the essential feature resides in an inkstand having a frusto-pyramidal ornamental base, and provided with an arched cylindrical spiral spring arranged at the back of the said base.

15 The figure of the drawing is a perspective view of an inkstand showing my new design.

Referring to the drawing, 1 designates the

base of an inkstand of approximately frusto-pyramidal shape having an ornamental exterior, provided with raised disks.

8 designates an arched spiral spring arranged at the back of the base and rising from the ends thereof.

25 It will be seen that the inkstand presents an ornamental and attractive appearance.
